(57) **CLAIM**

The ornamental design for a roping toy, as shown and described.

DESCRIPTION

FIG. 1 is a perspective view of a roping toy showing my new design;

FIG. 2 is a front elevation view thereof;

FIG. 3 is a rear elevation view thereof;

FIG. 4 is a left side elevation view thereof, the right side view being a mirror image thereof;

FIG. 5 is a top plan view thereof;

FIG. 6 is a perspective view of a roping toy showing an alternative embodiment of my new design;

FIG. 7 is a front elevation view thereof;

FIG. 8 is a rear elevation view thereof;

FIG. 9 is a left side elevation view thereof, the right side view being a mirror image thereof; and,

FIG. 10 is a top plan view thereof.

The bottom view of my roping toy is omitted and forms no part of the claimed design. The dashed lines in FIGS. 1-5 are shown for environmental purposes only and form no part of the claimed design.
